UNITED STATES PATENT OFFICE.

PETER D. HORTON, OF NEVADA CITY, CALIFORNIA, ASSIGNOR TO WILLIAMS & ROGERS, OF ROCHESTER, NEW YORK.

PENMANSHIP-GUIDE.

SPECIFICATION forming part of Letters Patent No. 417,559, dated December 17, 1889.

Application filed October 19, 1889. Serial No. 327,528. (No model.)

To all whom it may concern:

Be it known that I, PETER D. HORTON, of Nevada City, county of Nevada, and State of California, have invented certain new and useful Improvements in Penmanship-Guides; and I do hereby declare the following to be a full, clear, and exact description of the same, reference being had to the accompanying drawings, forming a part of this specification, 10 and to figures of reference marked thereon.

My present invention relates to penmanship-guides by which to determine the proper slant of the letters when formed according to the Spencerian or any other desired system, 15 and has for its object to provide a guide that is simple in construction and may be made and sold at a nominal price; and it consists in certain novelties of construction and combinations of parts, all as will be hereinafter 20 described, and the novel features pointed out in the claims at the end of this specification.

In the drawings, Figure 1 is a perspective view of the guide; Fig. 2, a top view showing the manner of using it, and Fig. 3 a sectional view. 25

Similar figures of reference denote similar parts.

The body of the guide consists of a suitable card or sheet 1, of card-board, wood, celluloid, 30 or any other suitable cheap and serviceable material, having a suitable opening 2 therein, preferably rectangular, but at any rate provided with the lower side straight, and across said opening projects a straight index filament or line 3, arranged in the present instance at an angle of fifty-two degrees from the bottom portion of the opening, or at such other inclination as it may be desired to have the letters slant. I prefer fifty-two degrees, 35 because this is the slant given the characters in the Spencerian system generally in use in schools, and is that of the straight lines of the small letters.

This index may consist of a thread or strip 40 of any suitable thin material that will afford a clear view on both sides of it; but I prefer to make it of a needle which may be secured in any suitable manner, but preferably by inserting it through the edge of the card-board, 45 the latter closing over its end when pushed

in far enough, preventing its accidental withdrawal or displacement.

The face of the card or sheet has preferably printed or marked upon it a number, or, if desired, all of the Spencerian characters, with 55 directions for the use of the guide.

In using the guide the operator first forms the character and then "tests" it, so to speak, by holding the guide over it with the lower portion of the aperture horizontal or parallel 60 with the base-line, on which the letter is formed, when the needle should be parallel with the straight line of the letter, if correctly formed, or should bear such relation to it, if a capital letter, as indicates the proper slant 65 as exhibited on the card.

By employing a needle or thread projecting across an opening in a guide the user can see the whole of the letter tested and readily ascertain wherein the fault, if any, lies, and is 70 thereby enabled to correct it readily, and by employing a clear opening instead of making the whole card transparent with a line thereon a better view can be had of the letter and there is no liability of its being obscured from 75 any cause—such as the scratching of a transparent card—or, if made of transparent gelatine or celluloid, of the cards becoming warped or twisted by heat or of being easily fractured. 80

Instead of the needle being inserted through the edges of the card, as shown, it will be understood that it could be secured in place by wafers or by a covering pasted on the card having the characters printed thereon, the 85 needle or index being previously laid on the card over the aperture in proper position.

I claim as my invention—

1. A penmanship-guide consisting of a card having an aperture therein and a needle or 90 index-line extending across said aperture at the proper angle relative to one of its sides, as set forth.

2. In a penmanship-guide, the combination, with a card having a series of characters 95 thereon, with lines indicating their proper inclination, and an aperture therein, of a needle or index extending across said aperture at the proper angle relative to one of its sides, substantially as described. 100

3. A penmanship-guide consisting of a card having an aperture therein and a needle inserted longitudinally in the card and extending across said aperture at the proper angle
5 relative to one of its sides, substantially as described.
4. The combination, with the card having

an aperture therein and a needle or index extending across said opening, substantially as described.

PETER D. HORTON.
